UNITED STATES PATENT OFFICE.

ABE SELIGSTEIN, OF ST. LOUIS, MISSOURI, ASSIGNOR TO ROSENTHAL PAPER AND STATIONERY COMPANY, OF ST. LOUIS, MISSOURI, A CORPORATION OF MISSOURI.

DESIGN FOR WRAPPING-PAPER.

40,288.

Specification for Design.

Patented Oct. 5, 1909.

Application filed May 15, 1909. Serial No. 496,329. Term of patent 14 years.

To all whom it may concern:

Be it known that I, ABE SELIGSTEIN, a citizen of the United States, and a resident of the city of St. Louis and State of Missouri, have invented a new, original, and ornamental Design for Wrapping-Paper, of which the following is a specification.

My design consists in the features shown in the accompanying drawing which forms part of this specification.

I claim:

The ornamental design for wrapping paper shown.

ABE SELIGSTEIN.

In the presence of—

G. A. PENNINGTON,
J. B. MEGOWN.
